ABSTRACT: A container sleeve formed from a pair of asymmetrical blanks, each of the blanks including a symmetrical portion having a main panel and opposed side and end panels, the side panels having flaps extending from each end thereof, one of the side panels being foldably connected to a mirror side panel adapted to be folded against its adjacent side panel and glued thereto, to thereby make a blank having a side flap of double thickness. The second blank is turned through 180° along an axis passing therethrough and parallel to the side panels. The double-thickness side flap of one blank is then glued to the single-thickness side flap of the other blank, and vice versa. The method of making such a container sleeve is also comprehended herein.

CONTAINER SLEEVE

BACKGROUND OF THE INVENTION

1. Field of the Invention

This invention relates generally to a container formed from paperboard and is especially related to those containers having multithickness sidewalls whereby the container has good stacking strength. The process of making such a container is also contemplated.

2. The Prior Art

As far as is known, the art does not disclose a container sleeve adapted to be formed into a container having three thicknesses of board in the sidewalls to provide good stacking strength. Walls of three thicknesses of board are disclosed in Walshenbach U.S. Pat. No. 2,761,608, but such is achieved by nesting inner and outer containers. Walls of double thickness are taught in the U.S. Pat. Nos. to Geyer 2,556,915 and 2,565,682; George 3,007,622 and Demby et al. 3,285,492

SUMMARY OF THE INVENTION

The present invention has for its particular object the making of a container sleeve from a pair of identical cut and scored blanks which when folded and glued as disclosed herein result in a container having good stacking strength by reason of the fact that the laminated sidewalls thereof consist of more than two laminae.

DRAWINGS

FIG. 1 is a perspective view of a cut and scored blank for forming a container sleeve according to the present invention;

FIG. 2 is a view similar to FIG. 1, but showing a mirror side panel folded and glued across a side panel seen in FIG. 1;

FIG. 3 shows a first panel similar to FIG. 2 and a second panel formed like FIG. 2 but in overlying relationship thereto and turned through a 180° angle about an axis passing therethrough and parallel to the opposed side panels thereof;

FIG. 4 is a view similar to FIG. 3 and showing an alternate method whereby the container sleeve may be formed;

FIG. 5 is an isometric view of a container formed from the carton sleeve according to the present invention; and

FIG. 6 is a vertical section taken substantially along the line 6-6 of FIG. 5 looking in the direction of the arrows.

SPECIFICATION

The carton sleeve according to the present invention is formed from a pair of cut and scored blanks 10 seen in FIG. 1 which when combined in the fashion as will be taught result in a finished carton 10A seen in FIG. 5.

The cut and scored blank 10 seen in FIG. 1 has a portion which is symmetrical about an axis A-A in the plane of the blank 10 and extending midway of a main panel 11 and parallel to a side panel 12 hingedly connected to main panel 11 and foldable with respect thereto along score lines 13. Each of the side panels 12 has end flaps 14 foldably connected thereto along score lines 16.

The symmetrical blank thus far described is asymmetrical by the provision of a mirror-extension side panel 12A hingedly connected to one of the side panels 12 at a score line 19. Such mirror-extension side panel 12A has a mirror-extension end flap 14A at each end thereof foldable with respect to the mirror-extension side panel 12A along a score line 16A.

The upper face of the mirror extension panel 12A has glue applied thereto and is mirror-extension against side panel 12, so that the side panel 12 now has a double thickness as seen in FIG. 2 by the superimposed mirror extension side panel 12A and the mirror-extension side flap 14 thereof.

In forming a carton sleeve according to the present invention a second carton blank formed in the aforementioned manner 180° turned or phased through 180° about the axis

15 A-A and superimposed upon the first blank as described to provide an assembly referred to by the reference numeral 10B which is completed by the gluing of side panel 12 and the end flaps 14 thereof to the mirror-extension side panel 12A and the mirror-extension side panels 14A thereof.

20 Alternately the gluing step just described may be acknowledged by the two carton blanks being in the position seen in FIG. 4. Irrespective of whether the gluing operation is carried on as seen in FIG. 3 or FIG. 4 the finished carton sleeve has a sidewall of three-laminae thickness comprising 25 mirror-extension side panel 12A and two side panels 12, all glued together.

The sleeve formed in the aforementioned manner is then formed into a carton having a sidewall with a thickness of three laminae by folding of the end panel 17 against the folded

30 end flaps 14 and 14A, the end panels 17 being glued thereagainst.

The carton thus formed has good stacking strength by reason of the multithick sidewalls with particular reference to FIG. 6.

35 I claim:

1. A sleeve-type container having improved stacking strength characterized by laminated sidewalls of not less than three laminae comprising:

40 a. identical rectangular first and second cut and scored blanks each having:

i. a symmetrical portion consisting of a main panel, opposed side and end panels hingedly joined thereto;

ii. end flaps hingedly joined to the ends of each side panel;

iii. a mirror extension of one of said side panels and the end flaps thereof and being foldably connected to said

45 one side panel; and

iv. said mirror extension being folded with respect to said one side panel and glued thereto;

b. said second blank being turned through a 180° degrees angle about an axis passing therethrough and parallel to the opposed side panels thereof;

c. the resulting double-thickness side panel of said first blank being glued to the single-thickness side panel of said second blank; and

55 d. the resulting double-thickness side panel of said second blank being glued to the single-thickness side panel of said first blank.
